UNITED STATES PATENT OFFICE.

EDWARD A. EVER, OF WILMETTE, ILLINOIS.

RADIATOR-SHIELD FOR MOTOR-VEHICLES.

1,369,228.

Specification of Letters Patent. Patented Feb. 22, 1921.

Application filed February 27, 1919. Serial No. 279,610.

To all whom it may concern:

Be it known that I, EDWARD A. EVER, a citizen of the United States, residing at Wilmette, in the county of Cook and State 5 of Illinois, have invented certain new and useful Improvements in Radiator-Shields for Motor-Vehicles, of which the following is a specification.

This invention relates to improvements in 10 radiator shields for motor vehicles and the like adapted to be readily applied to the radiator and as readily removed, and one of the objects of the invention is to provide an improved, simple, durable, cheap and 15 compact device of this character by means of which the temperature of the radiator may be readily controlled by controlling the amount of air supplied to the radiator, especially when the vehicle is in motion.

20 A further object is to provide an improved device of this character adapted to be controlled from a remote point.

A further object is to provide an improved device of this character which will 25 be semi-automatic in operation, in that the speed of the vehicle will in a measure function to cause the device to operate to permit the air to be delivered to the radiator.

To the attainment of these ends and the 30 accomplishment of other new and useful objects as will appear the invention consists in the features of novelty, in substantially the construction, combination and arrangement of the several parts hereinafter 35 more fully described and claimed and shown in the accompanying drawing illustrating this invention and in which—

Figure 1 is a front elevation of a radiator having a shield applied thereto constructed in accordance with the principles 40 of this invention.

Fig. 2 is a vertical sectional view taken on line 2—2, Fig. 1.

Fig. 3 is a detail perspective view of a 45 portion of the shield.

Referring more particularly to the drawing the numeral 10 designates the ordinary motor vehicle radiator in front of which the shield is adapted to be arranged. The shield 50 consists primarily of a frame 11 preferably of a size to cover substantially the entire front of the radiator. This frame may be constructed in any desired or suitable man-

ner of any suitable material, preferably metal, the side members 12 of which are 55 preferably deflected laterally as at 13 and provided with a series of openings 14 forming bearings. Projecting transversely of the frame thus formed are a plurality of pivotally mounted wings or dampers which 60 may be of any desired configuration but are preferably constructed of sheet material bent into a substantial U-shape form to provide front members 15 and rear members 16. The front member 15 is preferably of 65 a width slightly greater than the rear member 16 and between these members is arranged a flexible element 17 constructed of felt, fiber, or any other material suitable for the purpose, which will act as a heat insulating medium. The element thus formed is supported by a bar 18 secured to the element in any desired or suitable manner and the ends of this bar 18 are journaled in the respective openings 14 of the frame so that, 70 when the wings or elements are assembled and connected with the frame they will be supported for pivotal movement with respect to the frame and with respect to each other. The front 15 of the elements is preferably of a width to terminate adjacent the pivot of the next lowermost wing and the material 17 is of a length to project over and behind the pivot of the next lowermost member. 75

The frame itself is preferably provided with insulating material 19 secured to the inner face thereof so that when the shield is placed in position, the insulating material will abut the face of the radiator. 80

The shield thus constructed is adapted to be supported and held in position for pivotal movement with respect to the radiator, in any desired or suitable manner such, for instance, as a bracket 20 preferably of 85 L-shape formation and which bracket is secured adjacent the base of the radiator in any suitable manner such as by means of fastening devices 21 connected with the bracket and passing through the radiator to 100 the rear thereof, at which point the fastening device is passed through a plate or element 22 and receives a nut 23. The bracket is provided with any suitable number of openings 24 adapted to receive an ear or 105 projection 25 on the frame of the shield.

These projections pass through the openings 24 and are preferably bent or deflected as shown to form a hook by means of which the shield will be securely held against accidental displacement.

In use, the shield abuts the face of the radiator so that the wings will be held against swinging movement. This will shut off the air from the radiator and as will be manifest when the vehicle is in motion the air striking the wings will be prevented from passing through the radiator. This will confine the heat so that the radiator will become properly heated so as to permit the bottom of the radiator to become heated as well as the top of the radiator.

When it is desired to lower the temperature all that is necessary is to swing the shield forwardly into the position shown in dotted lines in Fig. 2, or to any extent desired so that when the vehicle is in motion, the air currents striking the wings will cause them to swing about their pivots and thereby form open passages for the air currents through the shield to the radiator. The greater the speed of the vehicle the greater will be the deflection or pivotal movement of the wings when the shield is in the position shown in dotted lines in Fig. 2.

Should it be desired, however, to prevent the wings from swinging to such a great extent, the wings may be controlled by the position of the shield, that is to say, if the shield is swung forwardly only a slight distance in advance of the radiator, it will be manifest that as the air currents strike the wings they will be deflected only to the extent that they will engage the radiator and will be held against further pivotal movement. When the vehicle stops or slows down, the wings will drop by gravity to their normal positions and close or partially close the shield.

Any suitable means may be provided for shifting the shield such for instance as an operating rod 26, which may be detachably connected by one end as at 27, to the shield. The rod passes through the radiator 10, and the dash board 28^a, and terminates in a handle 29, in a convenient position for the operator. A series of teeth 30, may be provided on the operating rod which coöperate with a fastening device 31, and a spring 32, may be provided to act upon the rod and thereby maintain the teeth 30, in locking relation with the fastening member 31.

If desired an elastic member or spring 28, may be interposed between the shield and the radiator for the purpose of assisting in shifting the shield with respect to the radiator.

With this improved construction it will be manifest that there is provided a device which may be readily applied to any form of a radiator and the shield may be readily

removed by simply swinging the shield forward a sufficient distance to permit the extremity of the operating rod to be detached from the shield, after which the hooks 25, may be disengaged from the bracket 20, and the bracket may be allowed to remain upon the radiator where it will be out of the way.

While the preferred form of the invention has been herein shown and described, it is to be understood that many changes may be made in the details of construction and in the combination and arrangement of the several parts within the scope of the claims without departing from the spirit of the invention.

What is claimed as new is:—

1. A radiator shield for motor vehicles, said shield embodying a supporting frame, means for shifting the frame, and a plurality of wings supported by the frame for free swinging movement with respect to the frame.

2. A radiator shield for motor vehicles, said shield embodying a supporting frame, means for shifting the frame, and a plurality of wings supported by the frame for free swinging movement with respect to the frame, the movement of the wings with respect to the frame being controlled entirely by air currents.

3. A radiator shield for motor vehicles, said shield embodying a supporting frame, means supporting the frame for movement toward and away from the radiator, and a plurality of wings supported by the frame for free swinging movement with respect thereto.

4. A radiator shield for motor vehicles, said shield embodying a supporting frame, means supporting the frame for movement toward and away from the radiator, a plurality of wings supported by the frame for free swinging movement with respect to the frame and means for maintaining the frame in its adjusted position with respect to the radiator.

5. A radiator shield for motor vehicles, said shield embodying a supporting frame, means for supporting the frame for movement toward and away from the radiator, a plurality of wings supported by the frame for free swinging movement with respect to the frame, the said wings overlapping the pivot of the next lowermost wing, and means for maintaining the shield in its adjusted position with respect to the radiator.

6. A radiator shield for motor vehicles, said shield embodying a supporting frame, means detachably securing the shield to the radiator for movement toward and away from the radiator, a plurality of wings supported by the frame for free swinging movement with respect to the frame, and means for shifting the frame with respect to the radiator and from a remote point.

7. A radiator shield for motor vehicles, said shield embodying a supporting frame, means detachably securing the shield to the radiator for movement toward and away from the radiator, a plurality of wings supported by the frame for free swinging movement with respect to the frame, and means for shifting the frame with respect to the radiator and from a remote point, 5 the last recited means embodying means for maintaining the shield in its adjusted position with respect to the radiator.
8. A radiator shield for motor vehicles embodying a supporting frame, means connecting the frame with the radiator for swinging movement toward and away from the radiator, a plurality of elements connected with the frame and mounted for free swinging movement with respect to the frame, said elements embodying heat insulating material, and means for shifting the frame with respect to the radiator.
9. A radiator shield for motor vehicles embodying a supporting frame, means connecting the frame with the radiator for movement toward and away from the radiator, wings connected with the frame for movement therewith and for free swinging movement with respect thereto, said 20 wings extending across the radiator and movable with respect to the frame by the air currents, and means for maintaining the frame in its adjusted position with respect to the radiator.
10. A radiator shield for motor vehicles embodying a frame, a plurality of wings extending across the frame for free swinging movement with respect thereto, a bracket, means detachably connecting the shield with the bracket for swinging movement toward and away from the radiator, and means for swinging the shield toward and away from the radiator.
11. A radiator shield for motor vehicles embodying a frame, a plurality of wings extending across the frame for free swinging movement with respect thereto, a bracket, means detachably connecting the shield with the bracket for swinging movement toward and away from the radiator, an operating rod detachably connected with the shield for swinging the latter toward and away from the radiator, and means for maintaining the shield in its adjusted position with respect to the radiator.
12. A radiator shield for motor vehicles, said shield embodying a supporting frame, means for supporting the frame for movement toward and away from the radiator, a 50 wing element extending across the frame for bodily movement therewith and for free independent movement with respect thereto, and means interposed between the radiator and shield for assisting in moving the shield relatively with respect to the radiator.
13. A radiator shield for motor vehicles, said shield embodying a supporting frame, means for supporting the frame for movement toward and away from the radiator, a wing element extending across the frame for 70 bodily movement therewith and for free independent movement with respect thereto, means for moving the shield with relation to the radiator, and elastic means interposed between the radiator and shield for assisting in moving the shield with respect to the radiator.
14. A radiator shield for motor vehicles, said shield embodying a supporting frame, movable toward and away from the radiator, and a plurality of wings supported by the frame for movement with respect to the frame, and means for shifting the frame with respect to the radiator whereby the wings may be moved with respect to the 85 frame.
15. A radiator shield for motor vehicles, said shield embodying a supporting frame, a wing connected with the frame for swinging movement with respect to the frame, 90 and means for shifting the frame, the said movement of the frame allowing the said wing to swing with respect to the frame.
16. A radiator shield for motor vehicles, said shield embodying one or more wings 95 arranged in front of the radiator, a support for the wings and with respect to which support the wings have a free swinging movement, and means for controlling the degree of pivotal movement of the wings 100 with respect to said support.
17. A radiator shield for motor vehicles, said shield embodying one or more wings arranged in front of the radiator for free swinging movement, the said swinging 105 movement of the wings being controlled entirely by air currents, and means for controlling at will the degree of movement of the wings under the influence of said air currents.
18. A radiator shield for motor vehicles, said shield embodying a plurality of wings supported in front of the radiator for free swinging movement with respect to the radiator, and means for controlling the swinging movement of the wings whereby some of the wings may be swung about their pivots by the action of air currents upon the wings, to a greater extent than others of said wings.
19. A radiator shield for motor vehicles, 115 said shield embodying a plurality of wings supported in front of the radiator for free swinging movement with respect to the radiator, means for controlling the swinging movement of the wings whereby some of the wings may be swung about their pivots by the action of air currents upon the wings, to a greater extent than others of said wings, and means for controlling at will the first recited means.

20. A radiator shield for motor vehicles, said shield embodying a plurality of disconnected wings supported in front and in advance of the radiator and for free shifting movement with respect to the radiator, the movement of said wings being controlled by air currents.
21. A radiator shield for motor vehicles, said shield embodying a plurality of wings supported in front and in advance of the radiator for free shifting movement with respect to the radiator, the movement of said wings being controlled by air currents, and means adapting some of said wings to a greater shifting movement by said air currents than others of the wings.
22. A radiator shield for motor vehicles, said shield embodying one or more wings supported for free swinging movement independently with respect to each other and by the action of air currents thereon.
23. A radiator shield for motor vehicles, said shield embodying a plurality of shiftable elements arranged in front of the radiator, said elements being independently responsive in their shifting movement to the action of air currents.
24. A radiator shield embodying a plurality of wings supported in front of the radiator for pivotal movement with respect to the radiator, and independently with respect to each other and means for controlling such pivotal movements.
25. A radiator shield embodying a plurality of wings supported in front of the radiator for pivotal movement with respect to the radiator, and independently with respect to each other, means for controlling such pivotal movements, and means causing said wings to operate automatically.
26. A radiator shield embodying one or more wings supported in front of the radiator for swinging movement with respect to the radiator, said wing or wings being movable about their pivots by the air currents acting directly upon said wing or wings.

In testimony whereof I have signed my name to this specification, on this 19th day of February, A. D., 1919.

EDW. A. EVERSON.
